UTERINE PROLAPSE PREVENTIVE DEVICE FOR
USE ON SHEEP

Sylvanus R. Hunt, Roseburg, Oreg., assignor to Snively
Plastics, Roseburg, Oreg., a corporation of Oregon

Filed Mar. 14, 1969, Ser. No. 16,237

Term of patent 7 years

Int. Cl. D24—99

U.S. Cl. D83—1

FIG. 2

FIG. 3

FIG. 1

FIG. 4

FIG. 5

FIG. 6

FIG. 1 is a front elevation of an intra-uterine device showing my new design;

FIG. 2 is a top plan view thereof;

FIG. 3 is an end view as seen from the left of FIG. 1;

FIG. 4 is an end view as seen from the right of FIG. 1;

FIG. 5 is a bottom plan view of the device; and

FIG. 6 is a rear elevation of the device.

I claim:

The ornamental design for a uterine prolapse preventive device for use on sheep, as shown and described.
